UNITED STATES PATENT OFFICE.

JOSEPH WILLIAM GIBNEY, OF NEW HAVEN, CONNECTICUT, ASSIGNOR TO THE SENTINEL MFG. CO., OF NEW HAVEN, CONNECTICUT, A CORPORATION.

GAS-VALVE.

1,218,252.

Specification of Letters Patent.

Patented Mar. 6, 1917.

Application filed October 18, 1915. Serial No. 56,439.

To all whom it may concern:

Be it known that I, JOSEPH W. GIBNEY, a citizen of the United States, residing at New Haven, in the county of New Haven and State of Connecticut, have invented a new and useful Improvement in Gas-Valves; and I do hereby declare the following, when taken in connection with the accompanying drawings and the characters of reference 5 marked thereon, to be a full, clear, and exact description of the same, and which said drawings constitute part of this application, and represent, in—

Figure 1 a view in side elevation of a 15 gas-valve constructed in accordance with my invention.

Fig. 2 an edge view thereof, with the long arm of the valve-operating lever in transverse section.

Fig. 3 a view partly in side elevation, and 20 partly in vertical section, showing the valve closed.

Fig. 4 a corresponding view showing the valve open.

Fig. 5 a detached view in side elevation of 25 the valve-stem.

Fig. 6 a corresponding view of the valve.

My invention relates to an improvement 30 in gas-valves, the object being to provide a construction which dispenses with the necessity of packing the valve-stem.

With these ends in view, my invention 35 consists in a gas-valve having its valve-stem provided with an annular seal made independent of the valve proper and co-acting with a seat formed independent of the valve-seat.

In carrying out my invention as herein 40 shown, the valve-stem 2 is formed above its longitudinal center with an annular seal 3 having its upper end formed with a bevel 4, concentric with the said stem, and preferably formed integral therewith. The said seal 3 fits snugly into and reciprocates in a 45 circular chamber 5 formed in the valve-body 6 and having its upper end contracted to provide a seat 7 for the bevel 4 of the seal 3. The contracted upper end of the said chamber 5 merges into a passage 8 re- 50 ceiving the reduced upper end 9 of the valve-stem 2 and in turn merging at its up-

per end into the lower end of a conical valve-seat 10 formed in said valve-body 6 and receiving a conical valve 11 which normally closes a gas-passage 12 intersecting the valve-seat 10 and extending at a right angle to the axis of the valve-stem 2. The upper end of the valve-stem 2 co-acts with the lower end of the valve 11, the two being in close proximity. Upon its upper face, the valve 11 is furnished with a concentric shank 13 encircled by the lower coils of a helical spring 14 held in place by a threaded cup 15. The main portion of the valve-stem 2 has bearing in a retaining-nut 16 screwed into the lower end of the valve-body 6. The chamber 5, the short passage 8 and the bore of the retaining-nut 16, together form the valve-stem passage which is generally packed by packing material or by glands, but which I seal by the use of the seal 3 upon the valve-stem. As shown, the projecting lower end of the stem 2 is engaged for operation by the short arm 17 of a lever 18 hung upon a stud 19 in a forked bracket-arm 20 made 65 integral with the body 6, the said lever 18 being furnished with a long operating-arm 21. The valve-body 6 is furnished, as usual, with an inlet nipple 22 and an outlet nipple 23, the latter being furnished, as shown, 70 with a jet 24 which may be of any approved construction. Of course the means employed for the operation of the stem 2 are wholly immaterial, as they have no direct connection with the present invention. When the 75 valve 11 is upon its seat 10, the seal 3 is out of play, as shown in Fig. 3, in which position the valve 11 itself prevents any leakage of gas downward into any portion of the passage containing the valve-stem. 80 However, when the valve 11 is lifted above its seat 10, the bevel 4 of the seal 3 is lifted against the bevel-seat 7 formed by contracting the upper end of the chamber 5, whereby the valve-stem passage as a whole is closed 85 and sealed without the use of any of the packings or glands ordinarily employed, the seal 3 acting when the valve 11 is open, to close the passage 8 which is normally sealed 90 by the valve itself.

I claim:—

In a gas valve, the combination with a

valve-body having a conical valve-seat, a gas-passage directly intersecting the said valve-seat at a right angle to the axis thereof, and a valve-stem passage formed with a sealing-chamber and arranged co-axially with the said valve-seat; of a valve co-acting with the said valve-seat, a spring for sealing

the said valve, and a valve-stem movable independently of the said valve and located in the said valve-stem passage in position to lift the valve from its seat and furnished with a concentric seal co-acting with the said sealing chamber.

JOSEPH WILLIAM GIBNEY.
